United States Patent Office

Des. 194,081
Patented Nov. 13, 1962

194,081

LETTER HOLDER OR SIMILAR ARTICLE

Fred A. Vilberg, 6034 Childress, St. Louis, Mo.

Filed Mar. 5, 1959, Ser. No. 54,850

Term of patent 14 years

(Cl. D74—9)

FIG. 1.

FIG. 2.

FIG. 3.

FIGURE 1 is a top plan of a letter holder or similar article showing my design;

I claim:

The ornamental design for a letter holder or similar article, as shown.
